ELECTRIC HAIR DRYER

Louis J. De La Marter, Lexington and Frederick W. Perl, Mansfield, Ohio, and Joseph R. Mango, Midlothian, Ill., assignors to Westinghouse Electric Corporation, a corporation of Pennsylvania

Filed June 4, 1962, Ser. No. 70,391

Term of patent 14 years

(Cl. D86—10)

Fig. 1

Fig. 4

Fig. 2

FIG. 1 is a perspective view of an electric hair dryer showing our new design;

FIG. 2 is an elevational view from the side opposite that shown in FIG. 1;

FIG. 3 is an end elevational view; and

FIG. 4 is a perspective view thereof in open condition.

The dominant features of the design reside in the portions shown in full lines, a hose being shown in broken lines for illustrative purposes only.

We claim:

The ornamental design for an electric hair dryer, substantially as shown and described.
